US00D926325S

(12) **United States Design Patent** (10) Patent No.: **US D926,325 S**
(45) Date of Patent: **** Jul. 27, 2021**

(54) **WEARABLE MEDICAL MONITORING DEVICE**

(71) Applicant: **DexCom, Inc.**, San Diego, CA (US)

(72) Inventors: **John Charles Barry**, San Diego, CA (US); **Young Woo Lee**, San Diego, CA (US); **David A. Keller**, Encinitas, CA (US); **Louise Emma van den Heuvel**, Somerville, MA (US); **Carol Wood Sutherland**, Somerville, MA (US); **John Stanley Hayes**, San Diego, CA (US)

(73) Assignee: **DexCom, Inc.**, San Diego, CA (US)

(**) Term: **15 Years**

(21) Appl. No.: **29/717,217**

(22) Filed: **Dec. 16, 2019**

(57) **CLAIM**

The ornamental design for a wearable medical monitoring device, as shown and described.

DESCRIPTION

FIG. 1 is a top, front, and right side perspective view of a wearable medical monitoring device showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the wearable medical monitoring device that form no part of the claimed design.

1 Claim, 3 Drawing Sheets

Related U.S. Application Data

which is a division of application No. 29/654,373, filed on Jun. 22, 2018, now Pat. No. Des. 870,291.
